UNITED STATES PATENT OFFICE.

CHARLES L. HORACK, OF BROOKLYN, NEW YORK.

AUTOMATIC FIRE-EXTINGUISHER.

SPECIFICATION forming part of Letters Patent No. 270,952, dated January 23, 1883.

Application filed August 19, 1882. (No model.)

To all whom it may concern:

Be it known that I, CHARLES L. HORACK, a citizen of the United States, residing at Brooklyn, in the county of Kings and State of New York, have invented a new and useful Improvement in Automatic Fire-Extinguishers, of which the following is a specification.

The object of this invention is to construct an automatic fire-extinguisher in such a manner as to employ one or more outlets from a cup containing extinguishing-fluid, and to keep said outlets closed by a valve or cap until released by the heat of a fire, and to provide a suitable distributor for the extinguishing-fluid by means of one or more deflectors combined with the discharge-nozzle.

Another object of this invention is to place and maintain a deflector so employed in a position where it would be least exposed to accidental strokes until it was actually required for deflecting the extinguishing-fluid. I therefore do not adjust the same in front of the outlet or outlets, but arrange it in a position where it is not attached to the valve closing the outlet, and from which it is only removed to assume a position suitable for deflecting the extinguishing-fluid by its weight or the action of fluid escaping through the opening or openings in the distributing-cup or by any other agency designed and arranged to accomplish said change in position of the deflector when the same becomes necessary or desirable.

A further object of this invention is to construct the device in such a manner as to keep the cap or valve confining the extinguishing-fluid in position by means of a number of fusible-solder joints or other similar devices to be broken by the heat of a fire, and arranged in such a manner as to allow the cap or valve closing the outlet or outlets for the extinguishing-fluid to become relieved and to be removed as soon as one of said destructible joints is broken, as more fully described hereinafter.

I attain these objects in the manner illustrated in the accompanying drawings, forming part of this specification.

Figure 1 represents a vertical section, and Fig. 2 a side elevation, of a device constructed according to my invention. Fig. 3 is a detail drawing relating to said Figs. 1 and 2. Fig. 4 also represents a vertical section, and Fig. 5

a side elevation, of a device so constructed; and Fig. 6, a detail drawing relating to said Figs. 4 and 5.

In Fig. 1, V represents a cap-shaped valve placed over the outside of and surrounding a discharge-nozzle or distributor, C, which is shown to have in its outside walls two circular openings, passing around the same and arranged to produce intersecting streams. In order to be able to make each of the two openings O continuous around the distributor C, I provide a stem, b, inside of the sprinkling-cup C, and fastened to the same or connected with it above, between and below the perforations O, using for such purpose, also, the arms a. (Shown in the drawings in Fig. 1.) The outside of the distributor has at its lower end a rim, r, projecting beyond the perforated part of the distributor. The valve V, which has a seat above and another one below the perforations, is shown to be partly balanced by or partly balancing the pressure of the extinguishing-fluid, although a valve fully balanced, or one not balanced at all or to any extent, by the pressure of the extinguishing-fluid might be used in this connection. Said valve V is made of two pieces, one, which is ring-shaped, resting against the upper valve-seat, the other, which is cap-shaped, resting against the lower valve-seat. These two pieces are screwed together, and it will readily be seen that by means of the screw-thread so employed the length of the cap can be regulated, and thereby a close joint upon both valve-seats can be secured. The spiral spring S is attached to the casting W, conveying the extinguishing-fluid to the distributor, and rests against a shoulder on the valve V, but need not necessarily be connected with said valve.

M M' are posts attached to said casting, having at their lower ends horizontal pivots p p. The horizontal bar N—a ground plan of which is represented in Fig. 3—has tapering slots J J at both ends, in which fit the pieces m and h, which are arranged to swing loosely around the pivots p p. I insert said pieces in the slots J J, as indicated in Fig. 1, and secure them there rigidly by means of solder fusible at a low temperature. Through the center of the piece N, I then pass the screw R, which I make rest against the valve V, and use for

forcing the valve V to its seats. If both of the soldered joints at J J should break at the same time, the bar N, and with it the screw R, would become detached entirely from the apparatus and would drop down, and the valve V, owing to its own weight and the action of the spring S resting against it, would be forced from its seats and would drop down sufficiently to allow the discharge of the extinguishing-fluid through the openings O O. The notches J J are shown in Fig. 3 to be wider on top than at the bottom and wider at the extreme ends of N than nearer the middle of said bar N. By making each slanting in two directions and by making the parts of m and h connected with them by solder correspond in shape with said notches, I facilitate the breaking of said joints. It frequently happens that one side of a fire-extinguisher is kept cool and wet by means of extinguishing-fluid being discharged by a neighboring extinguisher. This may either prevent it from coming into operation at all, or may at least delay it. By providing two or more soldered joints at different points, as indicated, I guard to a considerable extent against this difficulty, because it will be seen that even if only one of the joints should break the bar N, and with it the brace or screw R, will swing out of the way, and will allow the valve V to drop.

D is a ring-shaped piece, fixed temporarily above the openings O O, and is held there by the arms f f, which are attached to the valve V, but not to D, which simply rests or sits on the same. One-half of said ring-shaped piece D is shown in Fig. 2, which represents the device while in operation and after the valve V has dropped off. In the position shown in said Fig. 2, D acts as a deflector for the extinguishing-fluid passing through the openings O O, thereby creating a spray. The surface of the deflector directed toward said openings when the extinguisher is in operation is shown to be convex, although the same might be made concave, or with a straight slope, or with suitable projections, corrugations, or perforations, as might best serve to get a perfect distribution of the extinguishing-fluid.

Instead of having two arms f f attached to the valve V for supporting the deflector D in the position shown in Fig. 1, the lower or cap-shaped part of the valve V might be provided with a ring-shaped rim reaching up to the deflector while in said position, to support it there. This rim would also protect the spiral spring S; or the under side of the deflector might be extended downward, so as to rest directly upon the lower or cap shaped part of the valve V. Another way to hold the deflector D in the position shown in Fig. 1, and entirely independent of the valve V and its movements, would be to attach the same to the casting W by means of solder fusible at a low temperature, so as to have it drop at the time the valve V leaves its seat, or else to connect it with the casting W by means of mate-

rial such as would be reached and destroyed by the action of the extinguishing-fluid after the valve V had dropped. The shoulders near the lower ends of the posts M M serve to support the deflector when in the position shown in Fig. 2. The spiral spring S being connected with the casting W, but not with the valve V, it will assume the position shown in Fig. 2 after the valve V has left its seat, and will thereby assist in cutting up the water before it reaches the outer deflector, D. Ordinarily, however, it will be sufficient to employ only the deflector D, and in this case the spring S would have to be adjusted so as to drop off with the valve V, and would then have to be connected with said valve, and would only be made to rest on the casting W. Having a side opening in a discharge-nozzle and a deflector, D, in the position shown in Fig. 2 will spread the water in an upward direction and over a ceiling much better than any other style of deflector used heretofore.

While the walls of the distributor C have a recess containing the outlet or outlets, the walls of the valve V facing the same are provided with a recess in the opposite direction. This prevents any catching of the valve V on C while said valve V is moving downward to clear the openings O O.

Many of the details shown in this device in Figs. 1, 2, and 3 might be varied. The valve V might be made of only one piece. The spring S might be omitted altogether; and, instead of using the screw R for adjusting and forcing to its seats the valve V, the screw-thread in the posts M M' might be made to perform these functions, in which case the bar N could be made to rest directly upon the valve V. Finally, only one soldered joint might be used for confining the valve and doing away with the pieces h, m, N, and R. Said joint might be made between the valve V and the casting W, passing around the upper edge of said valve V, and might be constructed water-tight. Even the posts M M' could be dispensed with by making the upper rim of the valve project inward far enough at several points to make the same come to a rest on the rim r of the distributor C after the valve had dropped far enough to allow the extinguishing-fluid to be discharged through the openings O O. The deflector D would then be held in a position corresponding with that shown in Fig. 2 by said valve or cap V. While a number of openings producing intersecting streams seems the best means of discharging the water from the cup C, any other arrangement of outlets or a single outlet might be employed instead. A spring might be used to assist in bringing the deflector D into the position opposite the openings O O, as shown in Fig. 2.

Fig. 4 represents a perforated distributor, C, having a number of openings, O O, for which, however, a single opening might be substituted. A cap-shaped valve, V, is forced to its seats

by means of the screw R passing through the tapering nut x, which again has fastened to it the two swinging arms P P by means of the soldered joints J J, which correspond in shape 5 with the outer surface of said round and tapering nut x, as shown particularly in Fig. 6, which represents a bottom view of this part of the device. The spring S is attached to the casting W, and until a fire occurs is kept in a 10 recess below the perforations O O, in the position shown in Fig. 4, by the valve V resting on it. As soon as one of the soldered joints J J breaks, the spring S will force upward and throw off said valve V, and will at the same 15 time assume the position shown in Fig. 5, in which position it will act as a deflector for the extinguishing-fluid. In this case, again, the breaking of one of the two soldered joints J J is sufficient to allow the valve V to be thrown 20 off. The fusible solder generally applied to automatic extinguishers where a joint is to be broken by the heat of a fire, and where said solder in making the joint is applied in a thin film between two metallic surfaces, will, before 25 it begins to fuse, very effectually resist any tendency of the parts soldered together to separate by sliding by each other. On the other hand, it does not possess sufficient strength to hold together the different parts connected by it where 30 even limited force is applied in a direction at or near right angles to such a joint. The curved form given to the joints in this case secures strength in every direction, without, however, preventing the prompt and complete separation 35 between brace and lever. However, as I propose to make the construction of this joint the subject of a claim in an application for a patent which I propose to submit, I do not do so here. Recesses in the walls of the distributor C, as well as in the walls of the valve V, are shown in a similar manner and for similar 40 purposes as was done in Fig. 1.

A check or stop might be arranged to allow the spiral springs shown in Figs. 2 and 5 to 45 expand only to a certain point, thereby regulating the distance between the coils, and consequently the distribution of the water or other extinguishing-fluid, while said spring was acting as a deflector.

50 I claim as new and wish to secure by Letters Patent—

1. A distributor for fluids, provided with a continuous outlet fully dividing in two parts its surrounding wall or walls, said two parts 55 being rigidly connected with each other by means of a center post, b, and arms a a, substantially as set forth.

2. A distributor provided with two outlets, each one of which divides the same horizontally, the outlets being so constructed as to produce intersecting streams, substantially as 60 set forth.

3. In an automatic fire-extinguisher, the combination of a discharge-nozzle provided 65 with an outlet fully dividing the same, the parts separated thereby being rigidly connected by

means of a center post, b, and arms a a, with a cap closing said outlet and arranged to be relieved by the heat of a fire, substantially as set forth.

4. In an automatic fire-extinguisher, the combination of a distributor having in its surrounding walls perforations producing intersecting streams, with a cap arranged to surround said walls until relieved by the heat of 75 a fire, substantially as set forth.

5. In a distributor for fluids, the combination of a discharge-nozzle having in its surrounding wall or walls one or more openings, with a cap arranged to surround said wall or walls, and 80 with a deflector upon which the fluid is discharged, substantially as set forth.

6. In a distributor for fluids, the combination of a discharge-nozzle provided with openings constructed to produce intersecting streams, 85 with a deflector for further distributing the extinguishing-fluid, substantially as set forth.

7. In a sprinkling apparatus, the combination, with a discharge-nozzle, of a spiral spring adjusted to act as a distributor for the fluid, 90 substantially as set forth.

8. In an automatic fire-extinguisher, the combination, with a distributor having one or more discharge-outlets, of a cap preventing the escape of the extinguishing-fluid through 95 said outlet or outlets until said fluid has been released by the heat of a fire, and a deflector adjusted to assume a position in front of said outlet or outlets when the cap has been released by the heat of a fire, substantially as set 100 forth.

9. In an automatic fire-extinguisher, the combination, with a discharge-nozzle, of a valve closing its outlet until released by the heat of a fire, and a device adjusted to enter 105 the space in front of said outlet, to act as a deflector for the extinguishing-fluid after the valve has left its seat, substantially as set forth.

10. In an automatic fire-extinguisher, the combination of a discharge-nozzle with a cap 110 constructed to prevent the discharge of the extinguishing-fluid until relieved by the heat of a fire, and a device resting upon or against said cap without being attached to it, and constructed to become a deflector for the extinguishing-fluid after the same has been liberated by the heat of a fire, substantially as 115 set forth.

11. In an automatic fire-extinguisher, the combination of a distributor containing one or more perforations in its surrounding wall or walls, and having a rim or projection, r, at or near its extreme end projecting beyond said walls, with a cap closing said outlet or outlets until released by the heat of a fire, said projection r being constructed to extend beyond the walls of the distributor and to maintain a space between the same and the walls of said cap while the latter is being removed from its position in front of the outlet or outlets, substantially as set forth.

12. In a distributor for fluids, the combina-

tion, with a discharge-nozzle, of a cap protecting said nozzle, the walls of the nozzle facing the surrounding walls of the cap, and the outer walls of the cap facing those of the nozzle being made to recede from each other, substantially as set forth.

13. In an automatic fire-extinguisher, the combination, with a discharge-nozzle or distributor provided with an outlet or outlets, of a valve provided with two seating-surfaces, the construction being such that the pressure of the extinguishing-fluid is exerted upon the valve between its two seats, the length of the

valve between its two seating-surfaces being adjustable, substantially as set forth.

14. In an automatic fire-extinguisher, the combination, with a discharge-nozzle, of a cup-shaped valve and a device provided with a number of soldered joints for confining said valve in its position until one of said joints has been broken by the heat of a fire, substantially as set forth.

CHARLES L. HORACK.
